DESIGN.

I. A. SHEPPARD.

COOKING RANGE.

No. 15,623.

Patented Dec. 16, 1884.

UNITED STATES PATENT OFFICE.

ISAAC A. SHEPPARD, OF PHILADELPHIA, PENNSYLVANIA.

DESIGN FOR A COOKING-RANGE.

SPECIFICATION forming part of Design No.15,623, dated December 16, 1884.

Application filed October 17, 1884. Term of patent 14 years.

To all whom it may concern:

Be it known that I, ISAAC A. SHEPPARD, a citizen of the United States, and a resident of Philadelphia, Pennsylvania, have invented or 5 produced a new and original Design for a Cooking-Range, of which the following is a specification.

My design for a cooking-range is fully shown in the accompanying photographic illustration. The range has a flat-top upper body, with reservoir-extension at the rear, and a lower body between the upper body and the hearth-plate.

The general design of each of the doors on 15 the sides of the range consists of an outer raised rim and a flat face or border surrounding a central raised panel, both the rim and border being ornamented with figures consisting of raised line-work, too fully shown in the 20 illustration to need any detailed description. The central panels of the reservoir-door, hot-closet door, and lower ash-pit door (adjacent to said hot-closet door) are also ornamented with raised line-work. The panel of the oven- 25 door has raised line-work along its outer portion, and is furnished with a central medallion ornamented with engraved or sunken

lines. At the end of the oven-door are the fire-place door and upper ash-pit door, the fire-place door having a central panel with 30 two glazed openings, and the upper ash-pit door a circular damper. At the end of the range are the upper damper-door and lower damper-plate, having the usual oblong openings, with ornamentation between said openings. Beneath the upper damper-door is an oblong panel, and at each end of the same an ornamented vertical panel, and beneath these panels are the end ash-pit doors, each having two glazed openings. On the end of the lower 40 body of the range is a raised panel ornamented with line-work of the same general character as that on the rest of the range.

I claim—

The design for a cooking-range, said design 45 consisting of the ornamentation described and shown.

In testimony whereof I have signed my name to this specification in the presence of two subscribing witnesses.

ISAAC A. SHEPPARD.

Witnesses:

JOHN M. CLAYTON,
HARRY SMITH.
